Primary Examiner — Elizabeth A. Albert(74) Attorney, Agent, or Firm — Tucker Ellis LLP

(57)

CLAIM

The ornamental design for an organizer, as shown and described.

DESCRIPTION

FIG. 1 is a perspective view of an organizer showing my new design.

FIG. 2 is a bottom view thereof.

FIG. 3 is a top view thereof.

FIG. 4 is a right side view thereof.

FIG. 5 is a left side view thereof.

FIG. 6 is a front view thereof; and,

FIG. 7 is an inverted rear view thereof.

The broken lines in FIGS. 1-7 are included for the purpose of showing portions of the organizer that form no part of the claimed design.

1 Claim, 4 Drawing Sheets(56)
